[57] CLAIM

The ornamental design for a combination seat and handbag, as shown and described.

DESCRIPTION

FIG. 1 is a perspective view of the combination seat and handbag showing our new design,

FIG. 2 is an end elevational view, the opposite end view being a mirror image thereof,

FIG. 3 is a side elevational view, the opposite side view being a mirror image thereof,

FIG. 4 is a bottom plan view,

FIG. 5 is a perspective view of the combination seat and handbag in open position; and

FIG. 6 is a side elevational view on a reduced scale, the broken lines depicting a chair being shown for illustrative purposes only.
